UNITED STATES PATENT OFFICE.

CLARK LAWRENCE TANNER, OF MILES CITY, MONTANA.

LUBRICATING DEVICE FOR WHEEL-FLANGES.

1,027,930.

Specification of Letters Patent. Patented May 28, 1912.

Application filed January 17, 1910. Serial No. 538,488.

To all whom it may concern:

Be it known that I, CLARK L. TANNER, a citizen of the United States, residing at Miles City, in the county of Custer and State of Montana, have invented a new and useful Lubricating Device for Wheel-Flanges, of which the following is a specification.

This invention relates to a device for automatically lubricating the flanges of locomotive drivers, and is especially useful on mountainous or other railroads where there are numerous curves in the track, so that by lubricating the flanges of the driving wheels, the life thereof will be greatly prolonged, as well as the life of the rails.

The invention has for one of its objects to improve and simplify the construction of apparatus of this character so as to be reliable and efficient in use, comparatively simple and inexpensive, and readily kept in running order.

Another object is the provision of lubricating means including separate nozzles for the wheels and oil drip cups connected with the nozzles in combination with a conduit leading from the steam exhaust pipe of the air pump of the air brake system so that the wheels can be lubricated with oil from the said cups and also the unused oil which passes from the air pump cylinder together with the water of condensation therefrom passing through the exhaust pipe.

With these objects in view and others, as will appear as the description proceeds, the invention comprises the various novel features of construction and arrangement of parts which will be more fully described hereinafter and set forth with particularity in the claims appended hereto.

In the accompanying drawings, which illustrate one embodiment of the invention, Figure 1 is a side view of the lubricating apparatus shown applied. Fig. 2 is a front view thereof. Fig. 3 is an enlarged sectional view taken centrally through one of the oil cups and the parts connected therewith.

Similar reference characters are employed to designate corresponding parts throughout the views.

The lubricating apparatus, designated generally by A, is supported on the locomotive in any suitable manner, preferably in front of the front drivers B of the locomotive, and the apparatus is provided with 55 separate discharging nozzles 1 having their discharge orifices located adjacent the flanges 2 of the driving wheels so that the latter will be kept lubricated for the purpose of preventing excessive friction and 60 grinding when the train passes around curves in the track.

The lubricating device for each wheel consists of an oil cup 3 which has its bottom connected by a pipe 4 with the upper 65 end of a receptacle 5 which contains a body of hair 6 or other fibrous material through which the oil percolates on its way to the nozzle 1. The lower end of the receptacle 5 has a short pipe section 7, the receiving 70 end of which is protected by a gauze 8 so as to prevent the hair from stopping up the passage in the pipe 7, and the nozzle 1 is flexibly connected with this pipe by a hose 9 which permits the nozzle to be accurately 75 positioned with respect to the flange of the driver. In the bottom of the cup 3 is a valve seat 10 with which co-operates a needle valve 11 that has its upper end threaded in the cover 12 of the cup and by means of the 80 hand wheel 13, the needle valve can be adjusted with respect to its seat to regulate the feed in the number of drops per minute.

The exhaust steam from the air pump mechanism of the air brake system contains 85 more or less lubricant and this exhaust steam in the form of water of condensation, together with lubricating oil removed therewith, is utilizable in the system of the present invention. For this purpose the 90 steam exhaust pipe coming from the driving cylinder of the air pump is connected with the lubricating devices for each wheel, this being accomplished by connecting a pipe 15 to a T coupling 16 with the exhaust pipe 14 95 and providing branches 17 from the pipe 15 connected with the lubricating devices at points between the oil cups and the receptacles 5. Water of condensation in the exhaust pipe 14 will find its way through the pipe 15 and branches 17 to the receptacles 5 and lubricating oil flowing through the pipe 14 will also find its way in the same direction. Exhaust steam also flows through the pipe 14 and into the pipe 15 and by the 100 branches 17 to the receptacles 5, but because of the fibrous material within the receptacles the exhaust steam does not as steam

105

flow directly to the nozzles 1, but is condensed by the retarding action of the fibrous material and the large radiating surface provided by the receptacles 5, so that the 5 receptacles 5 filled with fibrous material serve as condensers for such exhaust steam as has not already been condensed and prevents steam from flowing through the receptacles 5 and so forcibly ejecting both steam 10 and water and oil against the flanges, which latter are thereby lubricated by both waste oil and water, and such additional lubricant as it may be necessary to supply from the cups 3, and such lubricating fluids are 15 not ejected forcibly against the wheel flanges as would occur if the exhaust steam had free passage to the nozzles 1, but the flow is retarded and the exhaust steam becomes condensed in its passage through the 20 condensers 5. The exhaust pipe 14 is shown as coming from an air pump structure 18, which may follow the usual practice in air brake systems, and this air pump is shown as under the control of a valve 19, as is 25 customary.

The device of the present invention is extremely simple and effective and has proven in practice to be highly efficient and satisfactory. No attention is required on 30 the part of the engineman, except to maintain the supply of lubricant in the oil cups. When traveling over comparatively long straight sections of track where no lubrication of the flanges of the wheels is required, 35 the needle valves may be closed to prevent waste of lubricant from the oil cups, but the escape of waste lubricant and water of condensation from the exhaust steam may continue, since there is no reason for preventing such escape.

From the foregoing description, taken in connection with the accompanying drawings, the advantages of the construction and of the method of operation will be readily 45 apparent to those skilled in the art to which the invention appertains, and while I have described the principle of operation of the invention, together with the device which I now consider to be the best embodiment 50 thereof, I desire to have it understood that the device shown is merely illustrative, and that such changes may be made when desired as are within the scope of the claims appended hereto.

Having thus described the invention, what I claim as new, and desire to secure by Letters Patent, is:—

1. A lubricating means for wheel flanges comprising a conduit including a section of 60 greater diameter than the main portion of the conduit and constituting a receptacle, fibrous material wholly inclosed in said receptacle, a nozzle connected to one end of the receptacle, and a steam pipe for conducting exhaust steam and waste lubricant to

the receptacle, said steam pipe being connected to the receptacle at the end thereof remote from the nozzle, and said receptacle with the fibrous material therein constituting a condenser for the exhaust steam. 70

2. A lubricating apparatus for wheels comprising a lubricant-containing cup, a valve for controlling the discharge of lubricant from the cup, a receptacle in the path of lubricant discharging from the cup and connected to said cup, said receptacle containing a body of fibrous material which the lubricant must traverse in its passage to the receptacle, a flexible conduit connected with the receptacle at the end remote from that connected with the lubricant containing cup, a nozzle secured to the end of the flexible conduit remote from said receptacle, and a connection with the receptacle between the same and the lubricant containing cup for the free flow of exhaust fluids thereto. 80

3. A lubricating apparatus for wheels comprising a conduit with a mass of fibrous material therein, a lubricant directing means at one end of the conduit, a lubricant cup at 90 the other end of the conduit and provided with means for controlling the flow of lubricant therefrom into the conduit, and means for the introduction of exhaust steam into the conduit between the lubricant cup and the fibrous material. 95

4. A means for utilizing the exhaust steam and waste lubricant from the pump driving means of an air brake system for causing the lubrication of wheel flanges, 100 comprising a conduit leading to a wheel flange and having an expanded portion adjacent the wheel flange and inclosing steam retarding and condensing means, and means at the discharge end of the conduit beyond the retarding means for directing fluids passing therethrough to the wheel flange to be lubricated. 105

5. A lubricating apparatus for wheels comprising a conduit terminating in a discharge nozzle for lubricant and provided with means for directing exhaust fluid into said conduit, retarding means for the exhaust fluid within the conduit between the point of entrance of the fluid and the nozzle, 110 and a lubricant cup connected to the conduit at a point therein more remote from the nozzle than the point of entrance of the exhaust fluid. 115

6. A lubricating apparatus for wheel flanges comprising a conduit terminating at one end in a nozzle in operative relation to a wheel and provided with a portion of enlarged diameter adjacent the nozzle, said enlarged portion containing loose fibrous 120 material wholly inclosed therein, the conduit having means beyond the end of the enlarged portion remote from the nozzle for connection to an exhaust steam pipe, and the fibrous material within the enlarged portion 130

- constituting a retarding and condensing means for exhaust steam reaching such fibrous material.
7. A lubricating apparatus for wheels comprising a conduit terminating at one end in a lubricant directing nozzle and including a flexible section adjacent the nozzle, said conduit also having means for the introduction of exhaust fluid, a retarding means for the exhaust fluid between the point of introduction of the exhaust fluid and the nozzle, and a lubricant cup connected to the conduit on the side of the exhaust fluid connection remote from the retarding means.
- 15 8. A lubricating apparatus for wheels comprising a conduit having an enlarged section containing fibrous material and at one side of said enlarged section having means for connecting an exhaust pipe thereto, the conduit at the end of the enlarged section remote from the steam connection being provided with a flexible portion terminating in lubricant directing means.
- 25 9. A lubricating apparatus for wheels comprising a conduit having an enlarged section containing fibrous material and at one side of said enlarged section having means for connecting an exhaust pipe thereto, the conduit at the end of the enlarged section remote from the exhaust pipe connection being provided with a flexible portion terminating in a lubricant directing nozzle, and a lubricant cup provided with means for controlling the flow of lubricant therefrom and connected to the conduit on the side of the exhaust pipe connection remote from the enlarged portion of the conduit.
- 35 10. An apparatus for lubricating the drivers of a locomotive comprising conduits for lubricant each having a discharge nozzle and including a section containing fibrous material through which the lubricant is directed, connections in the conduits for coupling an exhaust pipe thereto, said connections leading into the conduits on the side of the fibrous material remote from the nozzles, and controllable lubricant cups each connected to a respective conduit at a point more remote from the fibrous material than the connection for the exhaust pipe.
- 45 11. An apparatus for lubricating the drivers of a locomotive comprising conduits for lubricant having each a discharge nozzle and including a section containing

fibrous material through which the lubricant is directed, connections in the conduits for an exhaust pipe, said connections leading into the conduits on the side of the fibrous material remote from the nozzles, and controllable lubricant cups each connected to a respective conduit at a point more remote from the fibrous material than the connection for the exhaust pipe, said conduits each including a flexible section between the section containing the fibrous material and the discharge nozzle.

12. A lubricator for locomotives comprising in combination with driving wheels thereof, an air-brake pump carried thereby, a valve for controlling the supply of steam to said pump, and an exhaust pipe leading from said pump, a second pipe leading from said exhaust pipe and provided with branch pipes extending toward the sides of the engine, condensation chambers connected with said branch pipes, and discharge pipes located on opposite sides of the engine, and connected with said condensation chambers, each discharge pipe leading to a point adjacent a driving wheel flange and terminating in a nozzle adapted to direct a spray against the outer face of said driving wheel flange.

13. A lubricator for locomotives comprising in combination with driving wheels thereof, an air-brake pump carried thereby, a valve for controlling the supply of steam to said pump, and an exhaust pipe leading from said pump, a second pipe leading from said exhaust pipe and provided with branch pipes extending toward the sides of the engine, condensation chambers connected with said branch pipes, each of said condensation chambers containing hair, and discharge pipes located on opposite sides of the engine, and connected with said condensation chambers, each discharge pipe leading to a point adjacent a driving wheel flange and terminating in a nozzle adapted to direct a spray against the outer face of said driving wheel flange.

In testimony, that I claim the foregoing as my own, I have hereto affixed my signature in the presence of two witnesses.

CLARK LAWRENCE TANNER.
